CLAIM

The ornamental design for a solar LED light with mosaic pattern, as shown and described.

DESCRIPTION

FIG. 1 is a top front perspective view of a solar LED light with mosaic pattern showing my design therefor;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

Throughout the drawings the dotted lines indicate a border between claimed and unclaimed subject matter.
